UNITED STATES PATENT OFFICE.

GEORGE J. CARTER, OF KENTON, OHIO.

BRAKE-SHOE.

1,128,224.

Specification of Letters Patent.

Patented Feb. 9, 1915.

Application filed March 12, 1912. Serial No. 683,301.

To all whom it may concern:

Be it known that I, GEORGE J. CARTER, a citizen of the United States, residing at Kenton, in the county of Hardin and State 5 of Ohio, have invented certain new and useful Improvements in Brake-Shoes, of which the following is a specification.

This invention relates to brake shoes and has for its object to provide an improved 10 cast metal brake shoe so constructed that a part or parts of said shoe, when broken in transit or standing still will be prevented from becoming detached from the brake head and falling to the ground, and enabling the shoe to remain in use whether in 15 whole or in part.

The invention further has for its object to provide an improved brake shoe of this kind by means of which the hanger lug 20 will be protected and will coöperate in holding the parts of the brake shoe in place when broken.

Referring to the accompanying drawing: Figure 1 is a perspective view of a brake 25 shoe constructed in accordance with this invention. Fig. 2 is a sectional view along the line 2—2 of Fig. 1. Fig. 3 is a perspective view of the clip. Fig. 4 is a detail view in longitudinal section of a portion of the 30 brake shoe.

In the accompanying drawing 1 indicates a cast metal brake shoe having embedded therein steel bars or rods 2, which extend lengthwise thereof to a point adjacent to 35 each end of the shoe. The rods 2 are embedded in the shoe by placing them in the mold when the shoe is formed and pouring the metal around them. When so embedded, the rods 2 are fused at their extreme 40 ends for about $\frac{1}{2}$ inch and where they rest upon the hanger rod clip at the point 4. The object of fusing these rods at each end and where they come into contact with the clip 6 is for the purpose of holding those 45 rods securely in place and giving additional strength to the whole shoe and to the hanger lug. By fusing the ends of these bars 2, they become integral with the brake shoe. For the purpose of giving elasticity to the

shoe, the parts of the rods between these 50 points are not fused.

5 indicates the hanger lug, projecting from the back of the shoe. In order to protect the hanger lug and also to assist with the rods 2 in holding the parts of the shoe 55 together should it become broken, it is provided with a steel clip 6, consisting of a strip of metal formed with the top 7, extending over the top of the lug 5, and having the end portions 8 extending over the 60 ends of the lug 5, and into the sides of the shoe, and with the inturned flanges 9 projecting into the shoe and having at their inner end the upturned portion 10, the flanges 9 extending beneath the rods 2, and 65 the upturned portions 10 being located at one side thereof. The clip 6, like the rods, is placed in position in the mold before the metal is poured for the shoe, and has the lower portions of the ends 8 and the flanges 70 9 and 10 embedded in the shoe when the latter is cast. By this means the shoe is made stronger where the clip enters the shoe at the sides. In securing the clip in place the flanges 9 are fused to the rods 2. 75

It will be seen from the foregoing description, that when a brake shoe constructed as hereinbefore set forth becomes broken in one or several parts when in transit or standing still, the broken shoe will be held 80 together by the rods 2 and also by the reinforced hanger clip 6. By this means, the broken part or parts of a brake shoe will be prevented from falling into frogs, switches, grade crossings, or onto the rails, permitting 85 the shoe, although broken, to continue in use. The rods and clip are placed in position at the time the shoe is cast, and the shoe is constructed in such a way with the protecting parts that fusion is permitted only 90 when and where intended.

Having thus fully described my invention, what I claim as new and desire to secure by Letters-Patent of the United States, is:

A brake shoe provided with an integral hanger lug, a steel clip surrounding said lug and having inwardly and upwardly

bent ends embedded within the body of the
brake shoe, steel bars extending longitudi-
nally within the shoe and passing over the
inwardly bent ends of the clip and bearing
5 against the upwardly bent ends of said clip,
the ends of the clip and the bars being fused
together within the body of the shoe.

In testimony whereof I affix my signa-
ture in presence of two witnesses.

GEORGE J. CARTER.
